UNITED STATES PATENT OFFICE.

LOUIS JAUCH, OF SPRINGFIELD, OHIO.

KNIFE-SHARPENER.

No. 892,667.

Specification of Letters Patent.

Patented July 7, 1908.

Application filed July 29, 1907. Serial No. 386,002.

To all whom it may concern:

Be it known that I, LOUIS JAUCH, a citizen of the United States, residing at Springfield, in the county of Clark and State of Ohio, have invented certain new and useful Improvements in Knife-Sharpener, of which the following is a specification, reference being had therein to the accompanying drawings.

10 This invention relates to knife sharpeners of that class adapted to be attached to a convenient support and the blade of a knife drawn across the same in contact with the sharpening member.

15 The object of the invention is to provide a sharpener of this character which will be simple of construction and cheap in manufacture; in which the sharpening member can be adjusted relatively to the support so as to 20 bring a new part thereof into operative position when one part shall have become worn; which shall be so constructed and mounted as to form a rigid support for the sharpening member; and which will not vibrate when in 25 use, thus enabling the blade which is being drawn across the same to be maintained in constant engagement with the sharpening member, thereby producing a smooth, even edge on the blade.

30 With these objects in view my invention consists in certain novel features of construction and in certain parts and combinations hereinafter to be described, and then more particularly pointed out in the claims.

35 In the accompanying drawings, Figure 1 is a perspective view of my invention; Fig. 2 is a longitudinal sectional view, taken centrally through Fig. 1; and Fig. 3 is a transverse sectional view, taken on the line *x x* of Fig. 1 40 and looking in the direction of the arrows.

In these drawings I have illustrated the preferred form of my invention and have shown the same as consisting of a support having a base portion and an upwardly extending frame or housing, in which is rigidly mounted a sharpening member and which is provided with suitable guides for guiding the edge of the blade in contact with the sharpening member. In the form herein shown 45

50 this frame or housing is formed by bending upward one end of the base 1 at an angle thereto and then bending this upwardly turned portion downward upon itself in such a manner as to leave a space between the 55 two portions thereof, thus forming a housing 2 which preferably extends at an obtuse an-

gle to the base portion 1 and may, if desired, have a foot 3 extending substantially in alinement with the base 1 and serving to strengthen the housing 2 and hold the same 60 against vibration. The sharpening member preferably consists of a disk 9 of sharpening material, the material preferred being a very hard grade of steel. This disk is mounted within the housing 2 in any suitable manner, 65 but preferably by means of a bolt 4 extending through the wall of the housing and through the disk and provided with a nut 5 which enables the side walls of the housing to be clamped against the disk to secure the 70 same rigidly in position, but which will permit of the disk being adjusted within the housing by the mere loosening of the nut 5. The housing 2 has suitable openings adapted to expose the disk to view, and, as here 75 shown, the walls of these openings form the guides which support the blade in contact with the disk. The openings, which are shown at 6, preferably have their outer walls substantially vertical and their inner walls 80 extending at an acute angle thereto. The outer walls of the opening 6 preferably extend substantially parallel with the axis of the disk. The sharpener may be secured to the table or other supporting surface in any 85 suitable manner. I have here shown the same as secured in position by means of a bolt 7 extending through a slot 8 formed in the base 1 and engaging the table or other supporting member. 90

In operation, the support is secured to the table by means of a screw 7 extending through the slot 8 in the base 1 thereof and the blade of the implement to be sharpened is placed in the opening 6 against the outer walls 95 thereof with the lower edge in contact with the sharpening member or disk 9. The blade is then drawn through the opening in the direction of inclination of the housing 2, the contact of the edge of the blade with the 100 periphery of the disk 9 serving to sharpen the same and forming a slightly concave edge thereon. By repeating this operation on opposite sides of the disk the blade is sharpened on both sides thereof and a keen smooth edge 105 is formed thereon. The inclination of the housing 2 and the support 3 therefor serves to render the same practically rigid and prevent all vibration thereof, such as would tend to cause the blade to vibrate upon the disk 110 and prevent the same from being held in constant contact therewith. When that por-

tion of the periphery of the disk which is exposed becomes worn or smooth, the disk may be rotated to bring a new portion of the same into operative position by simply loosening 5 the nut 5 on the bolt 4, and, when the entire periphery of the disk shall have become worn, or filled with worn places, the disk may be removed and replaced in the housing in a reverse position, and, in this way, additional 10 sharpening surface secured. The support, which comprises the base and its housing, is of such a construction that it may be manufactured at a small cost, and the housing not only furnishes a support for the disk, but 15 also furnishes a protecting casing therefor which prevents injury to the same. The sharpening disks are made of a very hard brittle steel which is easily broken and it would be necessary to provide the same with 20 some protecting cover, which is here supplied by the housing 2.

While the device is designed particularly for attachment to a fixed support and to have the blade drawn across the same, it will be 25 apparent that when it is desired to sharpen a fixed blade, such as a mower knife, the base or support 1 may be used as a handle, and, by grasping the base in the hand, the device may be moved along the edge of the fixed 30 blade to sharpen the same.

I wish it to be understood that I do not desire to be limited to the exact details of construction shown and described, for obvious modifications will occur to a person skilled in 35 the art.

Having thus fully described my invention, what I claim as new and desire to secure by Letters Patent, is:—

1. A knife sharpener comprising a base, upwardly extending parallel walls forming a 40 housing and each having a notch in the upper edge thereof, and a disk mounted between said walls.

2. In a knife sharpener, a support comprising a base having an upwardly extending 45 inverted U-shaped portion forming a housing and having a notch formed in the upper edge thereof, and a disk mounted in said housing, having its diameter parallel with the walls thereof and its periphery adjacent to said 50 notch.

3. In a knife sharpener, a support comprising a base, an upwardly extending housing inclined away from said base and having a notch in one wall thereof, and a disk 55 mounted in said housing and having its periphery intersecting said notch.

4. In a knife sharpener, a support comprising a base portion having an upwardly bent inverted U-shaped portion intermediate 60 its ends, adapted to form a housing and provided with a notch in the upper wall thereof, and a disk mounted in said housing.

In testimony whereof I affix my signature in presence of two witnesses.

LOUIS JAUCH
